DISPLAY CART

Walter Gusdorf, 1042 Orchard Lakes, Creve Coeur, Mo.

Filed Oct. 30, 1964, Ser. No. 82,407

Term of patent 14 years

(Cl. D14—3)

FIG. 1 is a front perspective view of the display cart, showing my new design;

FIG. 2 is a side elevational view taken at the left side of FIG. 1, the opposite side being identical; and

FIG. 3 is a top plan view thereof.

The dominant features of my design reside in those portions shown in full lines.

I claim:

The ornamental design for a display cart, substantially as shown and described.
